UNITED STATES PATENT OFFICE.

WILLIAM BARTHOLOMEW, OF CHICAGO, ILLINOIS, ASSIGNOR TO TROY LAUNDRY MACHINERY COMPANY, LTD., A CORPORATION OF NEW YORK.

WASTE-VALVE.

1,261,895.

Specification of Letters Patent.

Patented Apr. 9, 1918.

Application filed May 8, 1914. Serial No. 837,209.

To all whom it may concern:

Be it known that I, WILLIAM BARTHOLOMEW, a citizen of the United States, residing at Chicago, in the county of Cook and State of Illinois, have invented certain new and useful Improvements in Waste-Valves, of which the following is a specification.

My invention relates to valves, and in particular to waste valves for washing machines or other fluid containing vessels.

In the construction of washing machines, particularly those of the rotating cylinder type, it is found to be desirable to locate the waste outlet on the lower side of the tank intermediate the ends thereof, in order to insure a ready and complete draining of the contents and it has been the usual practice to provide a waste duct or pipe leading from this outlet to a point adjacent the end or lateral wall of the tank where a valve may be conveniently located therein to control the discharge of the waste water. The portion of the waste pipe between the outlet from the tank and the valve forms a pocket in which the dirt and sediment from the interior of the tank collects to be later intermingled with the contents of the tank after a new charge of fresh water has been introduced therein.

To overcome this objectionable feature, I have provided an improved form of valve which is adapted to be located in close proximity to the outlet aperture in the bottom of the tank so that the waste water and suds or the like may be discharged directly downward from the tank into a suitable gutter or drain. By this construction a method is provided for thoroughly cleaning the tank of its waste contents so that no dirt or waste suds will remain to intermingle with the next charge of clothes and clean water. I further arrange my valve in combination with steam and fresh water inlet pipes, so that fresh water of any desired temperature may be introduced into the tank of the washing machine through the same aperture which serves as a discharge outlet.

A further object of my invention is to provide a valve for the purpose stated, which requires no stuffing-boxes to insure the efficient operation thereof.

A further object is to provide improved means for adjusting the valve relative to its seat.

Still another object is to provide a valve

of the kind referred to, which may be operated from a convenient position adjacent the washing machine.

Other objects will be set forth and made apparent in the following specification and accompanying drawings, in which I have chosen to illustrate and describe my invention as applied to a washing machine of the horizontal cylinder type.

In the drawing—

Figure 1 is a side elevation of the lower part of the tank of a cylinder type washing machine showing my invention applied thereto;

Fig. 2 is a side elevation of the header and inlet pipes showing a vertical longitudinal section of my improved valve in closed position;

Fig. 3 shows a vertical longitudinal section of my valve when in opened position;

Fig. 4 shows a transverse vertical section of the valve casing and associated parts; and

Fig. 5 shows a bottom plan view of the carriage member.

Like numerals are used to designate like parts and elements in the several figures of the drawings, in which 10 designates the tank of a cylinder type washing machine supported on the usual legs 11, and provided on its under side intermediate its ends, with an outlet aperture which is engaged by the upwardly extending annular flange 12 of a header 13, having the fresh water inlet pipe 14 and the steam pipe 15 leading thereto. The header 13 is provided with a laterally extending flange 16 which is adapted to be secured to the lower wall of the tank by suitable means to form a watertight connection therewith. The lower flange 17 is secured to and forms a similar tight connection with the outwardly extending flange 18 of a valve casing 19.

The valve casing 19 is provided with a duct 20 which is directly below the aperture in the tank and communicates therewith through the header 13. An annular valve seat 21 is formed at the lower end of the duct 20 and a valve cap 22 is arranged to coact therewith when in closed position to close the said duct. The valve cap 22 is preferably hollowed out within the walls of the duct 20, as shown at 22^a, in order to decrease the friction on the valve seat when the cap is moved to or from closed position.

The cap 22 is carried by a carriage member 23 which is adapted to slide on opposite guide flanges 24, formed on the inner walls of the casing 19, and thereby move the cap 22 substantially parallel to the plane of the valve seat 21. The carriage member 23 is provided at one side with upwardly turned lugs 25 between which is pivoted a connecting member 26 having the internally threaded socket 27 adapted to engage an operating rod 28 which is reciprocably mounted in the end wall of the laterally extending portion 19^a of the casing 19. The casing 19 is preferably so mounted on the header 13, that the rod 28 may be extended longitudinally of the tank beyond the end wall thereof where suitable means may be arranged for reciprocating the rod in order to slide the carriage member 23 on the guides 24 and thereby open or close the duct 20.

It will be observed that the guides 24 extend laterally into the portion 19^a of the casing and are provided with stops 24^a at their extremities so that the lateral movement of the carriage member will be limited at the point where the forward edge of the cap 22 is still engaging the valve seat, as shown in Fig. 3, where the valve is shown in open position. To prevent lateral swaying of the carriage member transversely to its direction of movement, said member is provided with shoulders 23^a which coact with the inner faces of the guide flanges 24, as shown in Fig. 4. The upper faces of the guide members 24 are preferably inclined slightly toward the valve seat in order that the valve will open readily and to further insure a tight seating of the valve cap when in closed position. The valve cap 22 is provided with a pair of symmetrically arranged depending lugs 29 which reciprocably engage the corresponding apertures 30 in the carriage member 23 whereby movement of the carriage member 19 on its guides 24 will cause a corresponding translation of the cap relative to its seat. A washer 31 is inserted between the carriage member and the cap member and is provided with apertures adapted to engage the lugs 29. Between the apertures 30 and directly beneath the center of the cap 22, the carriage member 23 is provided with a threaded aperture 32 which is engaged by a stud 33 having a slot 33^a in its end which may be engaged by a screw-driver or the like. A lock-nut 34 is adapted to engage the lower end of the stud 33 within the depression 34^a on the lower face of the carriage member and thereby maintain the said stud in any desired position relative to the carriage member. By means of this stud the distance between the cap and carriage member may be adjusted to regulate the pressure of said cap member on its seat.

From the foregoing description it will

be apparent that I have provided improved means for discharging the waste water from the interior of a washing machine or other vessel and that I have also provided means whereby fresh water may be introduced 70 through the same aperture that serves as a discharge outlet in the tank wall.

When it is desired to remove the waste contents of the machine, the rod 28 is moved to the left, as viewed in Fig. 2, 75 thereby opening the duct 20, as shown in Fig. 3, so that the contents of the cylinder may discharge directly downward without having to pass through any intermediate passage which may serve as a pocket for 80 the waste products. It will be apparent that during this discharge, none of the water comes in contact with the bearing 28^a of the rod or stem 28, so that it is entirely unnecessary to use a stuffing-box of 85 any description in order to insure a tight closure of the outlet duct. It is further apparent that after the parts become worn, the lock-nut 34 may be loosened and the stud 33 moved upwardly to force the cap 90 22 into tight engagement with the valve seat, after which the lock-nut 34 may be again tightened to preserve the parts in their new adjusted position. After a charge of waste water has been discharged from 95 the tank, the valve is again closed and steam and water may be introduced through the pipes 14 and 15 into the header 13, where they intermingle and then pass into the tank 10. By this arrangement it is apparent that the steam will combine with the 100 fresh water within the header 13, so that there is no danger of causing injury to the clothes within the tank by introducing hot steam directly therein.

I have shown and described my improved valve in connection with the header 13 and water and steam pipe 15, but it will be understood that the last named parts may be dispensed with in this connection, if desired, and the valve casing 19 secured directly to the wall of the tank.

While I have described in detail a particular form of my invention, as applied to a particular form of washing machine, 115 it will be understood that I have chosen these particular forms merely for the purpose of illustrating the principles and advantages of my invention, and I do not wish to be limited to the particular form or description, except as defined by the appended claims.

I claim:

1. In a device of the class described, a tank having an aperture in a wall thereof, a 125 header having a duct therethrough registering at its upper end with said aperture and at its lower end having a discharge opening, steam and water supply pipes entering said header and communicating with the 130

duct therein intermediate of its ends, and a valve controlling the discharge opening of the duct in said header whereby waste water may be discharged directly from or fresh water of any desired temperature introduced through said aperture.

2. In a device of the class described, a tank having an aperture in a wall thereof, a header having a duct therethrough registering with said aperture, a fluid supply conduit connected to said header and communicating with the duct therethrough, a valve casing secured to said header on the opposite side thereof from said tank and having a fluid discharge duct registering with the duct in said header, a valve seat around the duct in said valve casing, and a valve in said casing movable into and out of engagement with said valve seat.

20 3. The combination with a tank of a washing machine having an aperture through the bottom wall thereof, of a header depending from the bottom wall of said tank and having a vertical passage therethrough registering at its upper end with said aperture, steam and water supply conduits connected with said header and communicating with the passage therethrough intermediate of its ends, a valve casing secured to the lower end of said header and having a discharge passage registering with the passage in said header, and a valve located in said casing coöperating with a valve seat around the discharge passage therethrough.

35 4. The combination with a tank of a washing machine having an aperture through its bottom wall adjacent the center thereof, of a header depending from the bottom wall of said tank and having a vertical passage therethrough registering at its upper end with said aperture, steam and water supply conduits connected with said header and communicating with the passage therethrough intermediate of its ends and extending beneath said tank to one side thereof, a valve casing secured to the lower end of said header and having a discharge passage registering with the passage in said header, a horizontal bodily movable slide valve located in said casing and coöperating with the valve seat around the discharge passage therethrough, means within said

casing for guiding the valve into and out of engagement with said valve seat, and a rod pivotally connected with said valve and extending laterally therefrom through the valve casing for moving the valve relatively to said seat.

5. The combination with a tank having a discharge opening therefrom, of a valve seat around said opening, a bodily movable slide valve coöperating with said seat, a carriage member for said valve, said valve and member having complementary lugs and recesses for non-rotatably mounting said valve upon said member, adjusting means independent of said lugs on said member engaging said valve to adjust the same relatively to said member, guides in fixed relation to said valve seat, projections on said member resting upon said guides, and means for reciprocating said member relatively to said guides to thereby move said valve into and out of closed position with relation to said seat.

6. The combination with a tank having a discharge opening therefrom, of a valve casing having a passage registering with one end of the discharge opening of said tank, a valve seat in said casing around the other end of said passage, a bodily movable slide valve within said casing coöperating with said seat, a carriage member for said valve, said valve and member having complementary lugs and recesses for non-rotatably mounting said valve upon said member, a screw adjustably extending through said member and bearing against the adjacent surface of said valve intermediate of said lugs and recesses to adjust the valve relatively to said member, guides within said casing adjacent the valve seat, projections on said member resting upon said guides, and a rod pivotally connected to said carriage member and extending through said casing to move said member relatively to said guides and thereby open and close said valve.

In testimony whereof, I have subscribed my name.

WILLIAM BARTHOLOMEW.
